UNITED STATES PATENT OFFICE.

GEORGE F. CRIPPEN, OF YPSILANTI, MICHIGAN.

BEAN-PICKER.

SPECIFICATION forming part of Letters Patent No. 663,218, dated December 4, 1900.

Application filed September 25, 1899. Serial No. 731,659. (No model.)

To all whom it may concern:

Be it known that I, GEORGE F. CRIPPEN, a citizen of the United States, residing at Ypsilanti, in the county of Washtenaw and State 5 of Michigan, have invented certain new and useful Improvements in Bean - Pickers, of which the following is a specification, reference being had therein to the accompanying drawings.

10 My invention relates to bean-pickers; and the invention consists in the peculiar construction, arrangement, and combination of parts, with particular reference to the following points: first, the means employed for feeding and distributing the beans to the assorting devices; second, the peculiar construction of said assorting devices; third, the peculiar arrangement of a plurality of assorting devices in relation to one of the distributing devices, whereby the beans are alternately fed to said assorting devices; fourth, the means for cleaning the rolls constituting the assorting devices; fifth, the peculiar construction of a reciprocating gate 25 constituting an element of the distributing mechanism, and, sixth, the means employed for repicking the rejected beans.

The invention further consists in the peculiar construction and arrangement of parts, 30 as more fully hereinafter described, and specifically set forth in the claims.

In the drawings, Figure 1 is a perspective view of my bean-picker viewing the machine at one end. Fig. 2 is an elevation of the opposite end of the machine. Fig. 3 is a vertical cross-section through the machine. Fig. 4 is an enlarged sectional view of the assorting-rolls. Fig. 5 is a perspective view of the mechanism employed for reciprocating the 40 gates. Fig. 6 is a perspective view of the primary feeding devices of the beans. Fig. 7 is a vertical longitudinal section substantially on line xx , Fig. 3.

My bean-picker comprises, first, a hopper 45 or receptacle in which the beans to be picked are placed, and, second, one or more assorting devices, each of which comprises two rolls, one having a yielding surface and the other a hard unyielding surface, said rolls 50 being adapted to discriminate between the

good and poor beans, the latter being carried through between the rolls by frictional engagement therewith.

In addition to the above the machine, as shown in the drawings, comprises feeding 55 and distributing devices arranged between the hopper and the assorting devices, an oscillatory screen for cleaning the assorted beans, and a supplemental assorting device for the rejected beans.

More in detail the construction is as follows: A is the hopper, which is supported upon a suitable framework and is preferably provided with two tapering chutes A' A².

B represents feed-wheels mounted on rotary shafts B', extending longitudinally of the machine. Each feed-wheel is partially incased in a suitable housing a, secured to the bottom of the chutes A' A² and having an aperture a'', connecting with said chutes. The 65 feed-wheels are also provided with one or more pockets b, which in the rotation of the wheel are adapted to be filled with beans entering the casing a from the hopper A and to be subsequently emptied in the rotation of the 70 wheel. The feed-wheels are spaced from each other upon the shaft B' and are provided with means for simultaneously and correspondingly adjusting the size of the pockets 75 therein, comprising a series of heads c, sleeved upon the shaft B', each head being provided with a finger c', extending into the pocket b.

d is a rod or shaft extending parallel with the shaft B' and carrying a series of disks e, each of which is adapted to engage with a 85 groove c² in each of the heads c. The shaft d is slidily secured in suitable bearings f and is adapted to be reciprocated therein by a lever g, having a fork engaging with one of the disks e.

The mechanism just described enables the operator at any time to adjust the size of the pocket d by moving the lever g, which will cause the longitudinal movement of the shaft d and disks e thereon, and a corresponding 90 movement of the heads c and fingers c', thereby enlarging or diminishing the size of the pockets.

Beneath the feed-wheels B on each of the shafts B' is arranged a trough C, adapted to 100

receive the beans emptied from the pockets b and having a longitudinal slot in the bottom thereof.

5 D is a vibratory wing arranged beneath the trough C, adapted in one position to direct the beans discharged through the slot in the trough to the right thereof and in its other position correspondingly direct them to the left.

10 E and E' are assorting devices arranged to the right and left of the wing D beneath one set of feed-wheels, and E^2 and E^3 are corresponding assorting devices similarly arranged beneath the other set of feed-wheels. Each one of these assorting devices is of the following construction: h is a roll having a yielding surface. This surface I preferably form by covering the core h' of the roll with a layer h^2 of elastic material, such as soft rubber. Surrounding this layer is an outer detachable facing-sleeve h^3 , which is also preferably formed of rubber, but of a harder nature, better adapted for forming the surface of the roll. Beside the roll h is arranged a second roll i , this roll being preferably formed 25 of metal or other hard substance. The roll i is provided with the longitudinal channel i' , extending the length of the roll. A portion i^2 of the remaining surface of the roll x is smooth, while another portion i^3 is slightly 30 roughened, preferably by forming longitudinal serrations. The roll i is journaled in fixed bearings to the frame of the machine; but the roll h is preferably journaled in the ends of levers j , fulcrumed to the frame and provided 35 at opposite ends with adjusting means, whereby the position of the roll h relative to the roll i may be adjusted. The adjusting means which I preferably use consists of threaded rods k , extending across each end of 40 the machine and secured to the frame thereof, the ends of the levers j projecting into proximity to these rods and being held in different positions of adjustment by clamping-nuts k' on the rod k , while the degree of adjustment 45 is indicated by pointers k^2 , extending into proximity to scales k^3 , preferably secured to the rod k .

With the construction and arrangement of parts thus far described it will be readily understood that if motion be imparted to the rolls B , h , and i from suitable driving mechanism the beans in the hopper A will be periodically discharged in measured quantities by the feed-wheels B into the trough C and 55 then by means of the wings D directed alternately to the assorting devices on the right and left of said wings.

In order to control the discharge of the beans from the wing D to the assorting devices, so 60 that said beans will be arranged in a single row extending lengthwise of the rolls, I provide a gate F for each of the assorting devices, and which is constructed and arranged to operate as follows: The gate consists of a flat bar extending the entire length of the roll h and slidingly secured at its ends in suitable

bearings, such as the vertically-slotted posts l . This bar in its normal position rests with its lower edge in close proximity to the surface of the roll h , so as to arrest the beans discharged from the wing D. To facilitate the arrangement of the beans thus arrested in a single row, I provide means for oscillating the bar F longitudinally, which in the drawings I have shown as consisting of a rock-shaft m , 70 having rock-arms m' thereon, connected by the links m^2 with lugs l' on the bars F. Thus if the rocking movement be imparted to the shaft m the bar F will be given a corresponding longitudinally-reciprocating movement. I also provide means for periodically lifting the gate F to discharge the beans arrested thereby into the throat between the rolls h and i . To accomplish this, I preferably arrange a lever n , fulcrumed to the frame of 80 the machine and provided at one end with a fork engaging the post l beneath the end of the bar F. This lever also passes in proximity to the roll i' , and the latter is provided with a lug or cam n' , which is adapted in the revolution of the roll to elevate the lever n , and thereby to raise the gate F, as shown in Fig. 5 of the drawings.

To keep the surface of the rolls h and i perfectly clean, brushes are provided, as shown 95 at G and H. The brush H is stationary and is mounted in position to bear against the roll i . The brush G, however, is mounted upon a rock-shaft and is adapted to periodically rock from a position in contact with the roll E' into contact with the roll E.

J, J' , J^2 , and J^3 are wings arranged beneath and in proximity, respectively, to the rolls of the assorting devices E, E' , E^2 , and E^3 . These wings are for the purpose of directing the rejected beans discharged from each assorting device into one channel and the good beans discharged into another channel.

K is a vibratory screen or riddle onto which the beans are discharged from the wings J. 110 This screen comprises a suitable framework suspended by the links K' from the frame of the machine and is given an oscillatory movement by connections which will be hereinafter described.

o is an inclined diaphragm arranged across 115 the top of this screen-frame, onto which the poor beans are discharged.

p is a diaphragm arranged beneath the diaphragm o for collecting the good beans. 120 These diaphragms are arranged to respectively direct the beans discharged thereon onto the perforated screens q and r, which are inclined in the opposite direction, the former connected with the discharge-spout s and the latter discharging into a hopper t of an auxiliary assorting device E⁴. Beneath the screen r is an imperforate diaphragm u, adapted to catch the refuse passing through both of the screens and to discharge it into a suitable 125 waste-receptacle v.

I shall now describe the construction and

arrangement of connecting mechanism by means of which the parts thus far described are driven and timed in relation to each other.

M is a main shaft journaled in suitable bearings preferably in the lower portion of the frame of the machine, and extending parallel to the rolls *h* and *i*. Upon the shaft, at one end, are arranged sprocket-wheels connected by the sprocket-chains N and O with sprockets P P' and P' P' on the shafts of the rolls *h* of the various assorting devices. The arrangement of this sprocket-and-chain drive connection is such as to drive the adjacent rolls *h* in opposite directions, as indicated by arrows in Fig. 2 of the drawings. The sprocket-chain O also serves to drive the roll *h* of the auxiliary assorting device E⁴, as also indicated in Fig. 2. At the opposite end of the shaft M is arranged a train of gearing Q, forming a drive connection between said shaft and a shaft R, extending across the machine. This shaft R carries at its opposite ends eccentrics R', which are connected by the rods or links R² with the opposite ends of the screen-frame K. At the same end of the machine at which the gearing Q is arranged is a sprocket-and-chain connection between the shaft M and the sprocket-wheels S and S'. These sprocket-wheels are connected, respectively, by the chain S² with the rolls *i* of one of the primary assorting devices E² and of the auxiliary assorting device E⁴. On the same shaft with the sprocket-wheel S is arranged a gear-wheel T, which meshes with corresponding gear-wheels T', T², and T³ on the rolls *i* of the other assorting devices.

T⁴ and T⁵ are gear-wheels on the shafts B' and which mesh, respectively, with the gear-wheels T and T². U is a gear-wheel meshing with the gear-wheel T⁴ and mounted on a shaft U', extending across the machine. At the opposite end of the shaft U' is arranged an eccentric U², which is connected to a rock-arm m³ on the rock-shaft m.

V and V' are cranks arranged upon the shafts B' and at the opposite ends from the gear-wheels T⁴ and T⁵. The crank V has a lost-motion connection with a rod V², which at its opposite end is connected to a rock-arm D' for operating one of the vibrating wings D. This rock-arm is connected by a rod D² with a corresponding rock-arm D³ for operating the other vibratory wing D.

W and W' are rock-shafts extending through the chutes A' A² of the hopper A and carrying arms or wings for stirring the beans in the hopper and preventing them from becoming clogged. These rock-shafts are provided with rock-arms W², which are connected by the rod W³, having a connection W⁴ with the crank V'.

X represents cams arranged on the shafts of the rolls *i*, and X' represents rock-arms on the shafts of the wings J J' J² J³, respectively, (the one for the wing J alone being shown and in dotted lines in Fig. 3,) each of which arms

has a projection X², extending into proximity to the cam X, the arrangement being such that in the revolution of the cam X the arm will be rocked to throw the wing from one to the other of its positions.

Y is an eccentric on the shaft M, connected by the rods Y', Y², and Y³ with rock-arms for respectively actuating the rocking brushes G of the main and auxiliary assorting devices.

The parts being constructed as shown and described the complete operation of the machine is as follows: Motion being imparted to the shaft M it will communicate through the sprocket connections N and O to the rolls *h* of the various assorting devices, driving said rolls in the direction indicated by arrows. At the same time motion will be imparted to the shafts *i* through the sprocket connection S² and gear-wheels T T' T² T³ and through the gear-wheels T⁴ and T⁵ to the shaft B'. From the latter an oscillatory movement will be imparted by the cranks V and V' thereon to the rock-shafts W W' and rock-arms D' and D². Further motion will be imparted through the gear-wheel U, shaft U', and eccentric U² to the rock-arm m³, rock-shaft m, and rock-arms m', and the latter will impart a reciprocating movement to the gates F through the link connections m². It will thus be understood that the shafts B' will be rotated, causing the feed-wheels B thereon to periodically discharge a measured quantity of beans from the hopper A into the trough C. From this trough the beans will drop upon the wing D, which in the position shown in Fig. 3 will direct said beans to the right against the gate F of the assorting device E.

As before described, this gate F is given a longitudinal reciprocating movement through the shaft U', rock-shaft m, and rock-arm m', so that the beans arrested by said gate will be caused to arrange themselves in a single row. At a certain point in the operation the gate F will be lifted by the operation of the cam n' and lever n, which will lift the opposite ends of the gate and allow the beans to be carried into the throat between the rolls *h* and *i*. When this occurs, the roll *i* will be in a position where its surface i² will contact with the beans in the throat, and as this surface is perfectly smooth there will be but little frictional contact with the beans. Thus the good beans, which are smooth and hard, will remain in the throat between the rolls without being drawn between said rolls; but where the surface of the bean is very rough the friction of the roll therewith will be sufficient to cause it to be drawn in and discharged behind the wing J. This wing, in the position as shown in dotted lines in Fig. 3, is so arranged as to direct the beans thus

discharged onto the upper inclined diaphragm o of the screen-frame K, from which they will pass onto the lower perforated screen r. When in the movement of the roll *i* the roughened surface i³ thereof comes in con-

nection with the beans in the throat, the latter will be drawn into the roll *i* and be discharged behind the wing J. This wing, in the position as shown in dotted lines in Fig. 3, is so arranged as to direct the beans thus

discharged onto the upper inclined diaphragm o of the screen-frame K, from which they will pass onto the lower perforated screen r. When in the movement of the roll *i* the roughened surface i³ thereof comes in con-

tact with the beans, there will be a greater frictional engagement therewith, which will be sufficient to draw the beans between the rolls which were not affected by the smooth surface i^2 . However, if the surface of the bean is perfectly smooth and hard, as will be the case with a good quality of bean, the friction will not be sufficient to draw it between the rolls. After the roughened surface has 10 passed the throat the channel i' in the roll will receive such of the beans as have remained in the throat during the previous operation and will carry them through between the rolls. In the meantime the operation of 15 the cam X will have caused the rock-arm X' to move the wing J into its opposite position, as shown in full lines in Fig. 3, where when the beans are discharged from the channel i' it will direct them through the passage w onto the lower inclined diaphragm p of the screen-frame, from which they will be discharged 20 onto the upper perforated screen q .

During the operation just described the continued movement of the shaft B' will 25 cause the feed-wheels B to discharge another quantity of beans into the trough C ; but before they are so discharged the movement of the crank V will have operated the rock-arms D' and D^2 , causing the former to move 30 the wing D into the position shown in dotted lines in Fig. 3, where it will direct the discharged beans to the assorting device on the left of said wing. Here the operation will be repeated similar to the manner described 35 in connection with the assorting device E , and this alternate operation of the two devices will continue as long as the machine is in operation.

The operation of the assorting devices E^2 and E^3 , together with their feeding device on 40 the shaft B' at the left side of Fig. 3, will be precisely the same as that already described; but in Fig. 3 I have shown a slightly different position of parts at the left-hand side of 45 the figure in order to illustrate the various operations of the devices. Thus, in connection with the assorting devices E^2 , the gate F is shown as raised and the roll i in the initial position of its travel; also, the wheel B 50 is shown in a position where it is just beginning to discharge the beans collected in one of the pockets b . The good beans, which are discharged from the assorting devices E^2 and E^3 , are discharged by the wings J' , J^2 , and 55 J^3 , respectively, into the hoppers y , extending completely across the screen K and at their lower ends passing through the diaphragm o , so as to discharge the beans collected therein onto the lower diaphragm b . 60 At the same time these hoppers allow sufficient room on the diaphragm o between their lower ends to permit the beans discharged on the upper end of the diaphragm o to pass between said hoppers and to be discharged 65 onto the lower screen r . From the perforated screen q the good beans thereon will be discharged into the spout S into a suitable

receiving-receptacle. The beans on the screen r , however, are subject to a secondary assorting action by being discharged into 70 the hopper t of the auxiliary assorting device E^4 , which latter operates in a similar manner to those already referred to.

In order to secure a close separation, the vibratory wings D and J , J' , J^2 , and J^3 must 75 be provided with operating mechanism which is adapted to impart a quick movement to said wings at the time of reversal. This is accomplished in the case of the wings D by the lost-motion connection between the crank 80 V and the rock-arms D' , which, as shown in Fig. 2, consists of a sleeve x , to which the crank-pin is connected, slidably secured upon the rod V^2 , and the latter is provided with stops x' and x^2 , against which the sleeve 85 x is adapted to impinge when the crank V is in opposite positions. The movement of the wings J , J' , J^2 , and J^3 is effected by forming the cams X of the proper shape to impart a quick movement to the rock-arms X' , 90 while the springs X^3 serve to effect the opposite movement of said rock-arms.

As before stated, the brushes are rocked by the rods Y' , Y^2 , and Y^3 , to be alternately in contact with the rolls h of adjacent assorting devices. This movement of the brush not only dispenses with the necessity of having two brushes for the two rolls, but also effects a better cleaning of the roll in being drawn across the surface of the same than if said 100 roll were in contact with a stationary brush.

My machine may be readily adjusted to suit the requirement of different qualities of beans, first, by adjusting the quantity of beans fed, and this may be done by an adjustment of 105 the lever g , which will simultaneously and correspondingly move all of the sliding heads c and the fingers c' thereon, causing the pockets b in the feed-wheels to be correspondingly enlarged or diminished. A further adjustment may be effected by increasing or diminishing the distance between the rolls h and i , and this is readily accomplished by adjusting the nuts k^3 on the screw-threaded rod k , so as to change the positions of the 110 lever j , and thereby to move the rolls h . As all of these levers j extend into proximity to the same rod k , and as each is provided with a scale and index, a very accurate adjustment may be obtained.

It will be observed that the feed-wheels B have their pockets filled with beans in the upward portion of their rotary movement and are discharged after passing over the highest point. They thus constitute what I 125 shall term "overshot" wheels, and have the advantage of operating with less danger of choking than if rotated in the opposite direction.

What I claim as my invention is—

1. In a bean-picker, an assorting device comprising a pair of adjacent discriminating rolls one having a hard and the other a yielding surface said hard surface consisting of a

smooth portion and a roughened portion, adapted to successively act upon the beans, and means for discharging said beans after the action of the roughened surface.

5 2. In a bean-picker, an assorting device comprising a pair of adjacent discriminating rolls one having a hard and the other a yielding surface, said hard-surface roll being provided with a smooth portion, a following roughened portion, and a discharge-channel between the same and the smooth portion.

10 3. In a bean-picker, the combination with

a pair of adjacent discriminating rolls having a receiving-throat formed between and means 15 for feeding the beans to said rolls of a longitudinal reciprocating gate for arresting and alining said fed beans, and means for periodically lifting said gate to feed said alined beans into said throat.

20 In testimony whereof I affix my signature in presence of two witnesses.

GEORGE F. CRIPPEN.
